SHOPPING CART

Fred Pankiw, Weston, Ontario, Canada, assignor to Pan-Wal Mechanical Services Limited, Weston, Ontario, Canada

Filed May 4, 1971, Ser. No. 140,316

Term of patent 14 years

Int. Cl. D12—02

U.S. Cl. D14—3

FIG. 1

FIG. 2

FIG. 3

FIG. 4

FIG. 1 is a perspective view of a shopping cart taken from one side;

FIG. 2 is a perspective view thereof taken from the other side;

FIG. 3 is a side elevational view thereof taken from one side, the side opposite that shown being the same in appearance; and

FIG. 4 is a top plan view thereof.

I claim:

The ornamental design for a shopping cart, as shown and described.
